(57) **CLAIM**

An ornamental design for the closure element for packaging or containers, as shown.

DESCRIPTION

FIG. 1 shows a first perspective view of a first embodiment of the closure element for packaging or containers in accordance with the invention;

FIG. 2 shows a second perspective view of the first embodiment of the closure element for packaging or containers of FIG. 1;

FIG. 3 shows a third perspective view of the first embodiment of the closure element for packaging or containers of FIGS. 1 and 2;

FIG. 4 shows a top view of the first embodiment of the closure element for packaging or containers of FIGS. 1 to 3;

FIG. 5 shows a first side view of the first embodiment of the closure element for packaging or containers of FIGS. 1 to 4; FIG. 6 shows a second side view of the first embodiment of the closure element for packaging or containers of FIGS. 1 to 5;

FIG. 7 shows a third side view of the first embodiment of the closure element for packaging or containers of FIGS. 1 to 6; FIG. 8 shows a first perspective view of a second embodiment of the closure element for packaging or containers in accordance with the invention;

FIG. 9 shows a second perspective view of the second embodiment of the closure element for packaging or containers of FIG. 8;

FIG. 10 shows a third perspective view of the second embodiment of the closure element for packaging or containers of FIGS. 8 and 9;

FIG. 11 shows a top view of the second embodiment of the closure element for packaging or containers of FIGS. 8 to 10; FIG. 12 shows a first side view of the second embodiment of the closure element for packaging or containers of FIGS. 8 to 11;

FIG. 13 shows a second side view of the second embodiment of the closure element for packaging or containers of FIGS. 8 to 12;

FIG. 14 shows a third side view of the second embodiment of the closure element for packaging or containers of FIGS. 8 to 13;

FIG. 15 shows a first perspective view of a third embodiment of the closure element for packaging or containers in accordance with the invention;

FIG. 16 shows a second perspective view of the third embodiment of the closure element for packaging or containers of FIG. 15;

FIG. 17 shows a third perspective view of the third embodiment of the closure element for packaging or containers of FIGS. 15 and 16;

FIG. 18 shows a top view of the third embodiment of the closure element for packaging or containers of FIGS. 15 to 17;

FIG. 19 shows a first side view of the third embodiment of the closure element for packaging or containers of FIGS. 15 to 18;

FIG. 20 shows a second side view of the third embodiment of the closure element for packaging or containers of FIGS. 15 to 19;

FIG. 21 shows a third side view of the third embodiment of the closure element for packaging or containers of FIGS. 15 to 20;

FIG. 22 shows a first perspective view of a fourth embodiment of the closure element for packaging or containers in accordance with the invention;

FIG. 23 shows a second perspective view of the fourth embodiment of the closure element for packaging or containers of FIG. 22;

FIG. 24 shows a third perspective view of the fourth embodiment of the closure element for packaging or containers of FIGS. 22 and 23;

FIG. 25 shows a top view of the fourth embodiment of the closure element for packaging or containers of FIGS. 22 to 24;

FIG. 26 shows a first side view of the fourth embodiment of the closure element for packaging or containers of FIGS. 22 to 25;

FIG. 27 shows a second side view of the fourth embodiment of the closure element for packaging or containers of FIGS. 22 to 26; and,

FIG. 28 shows a third side view of the fourth embodiment of the closure element for packaging or containers of FIGS. 22 to 27.
